(57) **CLAIM**

The ornamental design for a movement assistance device—hip component, as shown and described.

DESCRIPTION

FIG. 1 is a front perspective view of a movement assistance device—hip component showing my design.

FIG. 2 is left side view thereof, the right side view being a mirror image thereof.

FIG. 3 is rear view thereof.

FIG. 4 is a front view thereof.

FIG. 5 is a top view thereof.

FIG. 6 is a bottom view thereof.

FIG. 7 is a front perspective view thereof, with the adjustment wings removed.

FIG. 8 is a front view thereof.

FIG. 9 is rear view thereof.

FIG. 10 is a left side view thereof, the right side view being a mirror image thereof.

FIG. 11 is a top view thereof; and,

FIG. 12 is a bottom view thereof.

It is understood that the appearance of any part of the article not shown in the drawing or described in the specification forms no part of the claimed design.

The broken lines shown in the figures represent portions of the movement assistance device—hip component that form no part of the claimed design.
